JAMES NAYLOR, JR., OF ARLINGTON, NEW JERSEY.

SUGAR-MAKING PROCESS.

1,172,303.

Specification of Letters Patent. Patented Feb. 22, 1916.

Application filed June 19, 1912. Serial No. 704,523.

To all whom it may concern:

Be it known that I, JAMES NAYLOR, Jr., a citizen of the United States, residing at Arlington, in the county of Hudson and State 5 of New Jersey, have invented new and useful Improvements in Sugar-Making Processes, of which the following is a specification.

My invention relates to sugar making and 10 consists of a new process whereby the sugar crystals are thoroughly washed, dried and separated from the mother-liquor.

My process is particularly adapted to be practised with a continuously operating, 15 centrifugal separator, and consists essentially in withdrawing the sugar and molasses separately from the separator heating a portion of the latter and returning it to the separator whereby the crystals are thoroughly 20 washed and dried and the operation of the machine promoted, all as hereinafter more fully explained.

My invention will be fully understood by reference to the drawing herewith in which— 25 Figure 1 is a diagram indicating the movements of the various portions of the mass, the better to explain my process. Figs. 2 and 3 show respectively in elevation and in plan a form of mechanism desirable for 30 practising my process.

In the figures A indicates a separator of any suitable construction, preferably a continuously operating centrifugal machine, for it is one of the great advantages of my process, that it may be used, and is preferably used with a continuous separator. To this separator the mother-liquor carrying the crystals from the crystallizing tanks or the masse-cuite from the mixer, as the case may 35 be, is delivered through the spout B.

D is the discharge opening for the dry sugar and C the discharge pipe for the molasses to the receiving-tank containing a submerged force-pump F driven by the connecting rod G from the mixer mechanism above.

From this receiving tank a portion of the molasses flows through the overflow H to the storage tank, but another portion is delivered by the pump through pipe J to coil N, 50 arranged in the heater I, all of ordinary construction and provided to heat the molasses passing through by exhaust steam from the main engine or any auxiliary pump. The molasses may be heated by other 55 means or by other mechanism. A tempera-

ture of 200° F. or more is desirable, and the hotter the better within certain limits.

From the coil the heated portion passes through the return pipe J' and is delivered into the separator, for instance at orifice K 60 adjacent to spout B, so that this heated portion mingles with the masse-cuite as it enters the centrifugal machine, whereby three important advantages are obtained. One, the crystals are thoroughly washed, two, the 65 sugar is heated so that the crystals absorb the heat and flash dry as they pass from the machine and three, the mass of liquid is thinned so that it will flow freely and the machine will operate. This last result is 70 very important, for heretofore on account of the thickness, viscosity or semi-fluid character of the masse-cuite, it has not been possible commercially to operate centrifugal machines in a continuous process. This 75 thinning of the mass is effected without in any way breaking, or melting, the crystals, for the time of contact of the heated molasses therewith is too short to produce any melting effect except that this has the additional advantage of keeping the discharge 80 openings of the machine washed clean. This washing the crystals in their own mother liquor is a peculiarity of my process and I believe to be absolutely new in itself. In the 85 present intermittent machines now in common use, hot water must be introduced, (which is wasteful and only partially washes the sugar) and without the hot water the sugar would be still worse. 90

It is evident that the size and speed of the pump will determine the quantity of liquid to pass through the heater, but this may be regulated and absolutely controlled by the relief valve L in pipe J and the regulating 95 valve M in pipe J', whereby the amount of excess molasses returned to the centrifugal machine may be exactly proportioned to the amount flowing in from the mixer so as to produce the best results without too much 100 returned in excess and therefore without waste of heat or power.

It may be assumed that of the whole mass passing through the separator approximately 60 parts more or less is sugar, and, 105 of the molasses, 15 parts more or less comes from the mixer and 25 parts is the amount returned, but I give these proportions merely by way of illustration to indicate a desirable amount to be heated and returned and 110

I do not propose to limit myself thereto, for the amount so returned may be varied for purposes of convenience and depending on special circumstances.

5 One of the most important advantages of my process is that it makes commercially possible the more rapid and therefore the more economical continuous process in place of the intermittent processes now in common use, for without the assistance of my process I do not believe that any continuous centrifugal machine would operate practically.

10 Having described my invention, I claim,
15 1. The herein described sugar making process which consists in introducing the masse-cuite into a separator, withdrawing the crystals and molasses separately therefrom, heating a portion of the molasses so withdrawn and returning said heated portion direct to the separator for admixture with the masse-cuite, while the separator is operating, to promote a more thorough washing and drying of the crystals.

20 2. The herein described continuous sugar making process which consists in continuously introducing the masse-cuite into a

continuously operating, centrifugal separator having a continuous and separate discharge both of the molasses and the sugar, 30 heating a portion of the discharged molasses and returning said heated portion immediately and directly to the separator to thin the liquid therein and to wash and flash dry the crystals.

35 3. The herein described continuous sugar making process, which consists in delivering the masse-cuite from the mixer to the separator, withdrawing the sugar and molasses separately from the separator, heating about 40 half of the molasses, more or less, so withdrawn, to at least about 200° F. and returning said heated portion immediately and directly to the separator, and at the point where the masse-cuite is being fed so that 45 the two will mix and the latter be thinned, permitting the separator to operate.

In testimony whereof I have signed my name to this specification in the presence of two subscribing witnesses.

JAMES NAYLOR, Jr.
